UNITED STATES PATENT OFFICE.

LEVINUS PHILIP DENOYER, OF KENILWORTH, ILLINOIS.

TIME DIAL FOR GLOBES.

Application filed November 17, 1924. Serial No. 750,482.

To all whom it may concern:

Be it known that I, LEVINUS P. DENOYER, a citizen of the United States, residing at Kenilworth, in the county of Cook and State 5 of Illinois, have invented certain new and useful Improvements in Time Dials for Globes; and I do declare the following to be a full, clear, and exact description of the invention, such as will enable others skilled 10 in the art to which it appertains to make and use the same.

This invention relates to improvements in dials adapted to be rotatably mounted at either or both poles of a celestial or terrestrial globe, and the invention further relates 15 to dials of this type commonly known as time dials. These time dials enable the user to determine the time at any place on the surface of the globe, corresponding to a given time at one particular place. In accomplishing this result, all other time dials heretofore devised, constantly obscure a certain portion of the globe. It is the object 20 of my invention however, to provide an improved type of dial which does not permanently obscure any area or areas of the globe, except one of infinitesimal size around the pivot of the dial.

With the foregoing in view, the invention 30 resides in the novel subject matter herein-after described and claimed, the description being supplemented by the accompanying drawing.

Figure 1 is a plan view of one form of 35 the improved dial and a portion of a terrestrial globe associated therewith.

Figure 2 is a sectional view on line 2—2 of Fig. 1.

Figure 3 is a plan view showing a slightly 40 different form of construction which may be followed if desired, the time graduations being omitted from this view on account of its relatively small size.

The numeral 1 designates the improved 45 time dial in a general way, said dial being adapted to be rotatably mounted at a pole of a globe and having its periphery formed of radially offset portions which will not obscure the same areas of the globe. Preferably, the dial comprises a rather small hub 2, a plurality of spokes 3 radiating from 50 said hub, and a narrow rim formed of radially offset portions connected to the spokes.

These portions may be of any desired number and lengths, and obviously any suitable 55 number of the spokes may be used. In the illustration, two radially offset portions 4 and 5 are provided to form the rim of the dial. The ends of these portions may be connected by certain of the spokes 3 as 60 shown in Fig. 1, or the spokes may be connected with the offset portions of the rim, in such a manner that the ends of said portions are free of direct connection with each other, this modification being illustrated in 65 Fig. 3. In either form of construction, the rim is provided with time graduations which are shown in Fig. 1, but omitted from Fig. 3 for the reason that the latter is drawn on a rather small scale.

It will be seen from the foregoing that by the use of my invention, one portion of the rim will at no time obscure an area of the globe obscured at another time by another portion of the rim. Hence, by turning the dial to one position or another, all upper portions of the globe may be readily seen except that portion directly under the hub 2, which is of little consequence. Attention may here also be directed to the fact 70 that with the unique construction of the device, it may be extended further from the pole toward the equator, than the old style time dial. This is very advantageous, for 75 with the old style dial, the latter would entirely cover up more important areas, if of a size to extend further toward the equator, but with the present invention, it would be possible to make the time dial extend down as far as 45° latitude and still make it 80 possible to show any part of the globe that may be desired. Moreover, the larger the rim of the dial is made, the more accurately it 85 may be graduated.

Excellent results are obtainable from 90 either of the constructions shown, but within the scope of the invention as claimed, other modifications may of course be made.

I claim:—

1. A dial adapted to be rotatably mounted 100 at one pole of a globe, said dial having its periphery formed of radially offset portions which will not obscure the same areas of the globe.

2. A dial adapted to be rotatably mounted 105 at one pole of a globe, said dial being of

openwork construction and having a peripheral rim formed of portions offset from each other for movement over different areas of the globe.

5 3. A dial adapted to be rotatably mounted at one pole of a globe, said dial comprising a hub, spokes radiating therefrom, and

a rim consisting of portions connected to said spokes and offset radially from each other for movement over different areas of the globe.

In testimony whereof I have hereunto affixed my signature.

LEVINUS PHILIP DENOYER.
